U.S. Cl. D26—1 E

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 14

FIG. 13

FIG. 15

FIG. 16

FIG. 17

FIG. 18

FIG. 19

FIG. 20

FIG. 1 is a front elevational view of a socket for relay showing our new design;

FIG. 2 is top plan view thereof;

FIG. 3 is a left side elevational view thereof;

FIG. 4 is a top, right, front perspective view thereof;

FIG. 5 is a bottom, left, rear, perspective view thereof;

FIG. 6 is an exploded view of FIG. 4;

FIG. 7 is a perspective view showing a second embodiment of FIGS. 1 through 6 wherein the only difference resides in the deduction of parts;

FIG. 8 is a perspective view showing a third embodiment of FIGS. 1 through 6 wherein the only difference resides in the duplication of parts;

FIGS. 9, 10 and 11 are top plan, top, right, front perspective and bottom, left, rear, perspective views respectively showing a fourth embodiment of FIGS. 1 through 6;

FIGS. 12 and 13 are top, right, front perspective and bottom, left, rear, perspective views respectively showing a fifth embodiment of FIGS. 1 through 6;

FIGS. 14 and 15 are top, right, front perspective and bottom, left, rear, perspective views respectively showing a sixth embodiment of FIGS. 1 through 6.

FIGS. 16, 17 and 18 are top plan, top, right, front perspective and bottom, left, rear perspective views respectively showing a seventh embodiment of FIGS. 1 through 6;

FIG. 19 is a perspective view showing an eighth embodiment of FIGS. 1 through 6 wherein the only difference resides in the configuration of the bottom which is substantially the same as that shown in FIG. 18 except for the width; and

FIG. 20 is a perspective view showing a ninth embodiment of FIGS. 1 through 6 wherein the differences reside in the configuration of the bottom which is substantially the same as that shown in FIG. 18 except for the width, and the duplication of parts.

We claim:

The ornamental design for a socket for relay, as shown and described.
